UNITED STATES PATENT OFFICE

142,212

DESIGN FOR A GAME BOARD

Dewey Dahlberg Gruver, Little Rock, Ark.

Application May 24, 1945, Serial No. 119,705

Term of patent 14 years

(Cl. D34—5)

To all whom it may concern:

Be it known that I, Dewey Dahlberg Gruver, a citizen of the United States, residing at Little Rock, in the county of Pulaski and State of Arkansas, have invented a new, original, and ornamental Design for a Game Board, of which the following is a specification, reference being had to the accompanying drawing, forming part thereof.

Figure 1 is a plan view of a game board showing my new design, and

Figure 2 is an edge elevational view thereof.

I claim:

The ornamental design for a game board, as shown.

DEWEY DAHLBERG GRUVER.
